J. ASHMAN

TWIN STEEL CROSSTIE

Filed Nov. 16, 1926

Fig. 2.

Fig. 3.

Inventor
JAMES ASHMAN,

Bernard W. Farney
Attorney

UNITED STATES PATENT OFFICE.

JAMES ASHMAN, OF CENTRAL CITY, PENNSYLVANIA.

TWIN STEEL CROSSTIE.

Application filed November 16, 1926. Serial No. 148,662.

The present invention consists of a combination twin cross tie and rail chair and has for an object to provide a substantial rail support and rail lock which will positively hold the rails from spreading as well as prevent separation of the rails at their jointure.

Other objects of the invention are to provide a combined tie and rail chair equipped with locking wedges to secure the fish plates from displacement; to provide a chair in which the rails may be conveniently and expeditiously inserted and from which the rails may be readily removed; and to provide a durable structure which is compact and may be assembled with facility by the ordinary track workers.

Further objects of the invention will be apparent from the following description of the present preferred form of the invention taken in connection with the accompanying drawings wherein:—

Fig. 1 is a perspective view of a combined cross tie and rail chair constructed in accordance with the present invention illustrating its application.

Fig. 2 is a transverse sectional view thereof; and

Fig. 3 is a detail fragmentary perspective view showing the rail chair and fish plates from the outside of a single rail.

The device of the present invention embodies a cross tie composed of a pair of I beams 4 preferably made of metal and equipped on their lower faces with right angle anchoring plates 5 which are adapted for penetration in the track ballast in order to prevent longitudinal displacement of the tie. It will be noted that the plates 5 span the distance between the two beams and are secured thereto in proximity to the ends of the beams making up the tie.

Mounted upon the upper faces of the tie are a pair of rail chairs 6 and 7, the former being used where a rail joint exists and the latter being used with a single or integral rail. The rail chair 6 is composed of a base plate 8 which spans the distance between the beams 4 of the tie in parallelism with the angle plates 5. These plates are bolted or otherwise detachably secured to the tops of the beams 4 and are equipped with superimposed clips 9 and 10. The clips are detachably engaged with the base plate and have the inner marginal edges thereof spaced apart for an appreciable distance to permit the insertion of rails 11 therebetween and like-

wise accommodate other structure which holds the rails to the chair, as hereinafter described. Fish plates 12 are superimposed on the base flanges of the rails 11 at the jointure of the latter and are detachably secured to the rail webs by nuts and bolts 13. It will be noted, especially upon reference to Fig. 2 of the drawings, that the lower margins of the fish plates are bent outwardly and snugly engage the upper faces of the base flanges of the rails. The clip 9 extends upwardly over the base portion of the inner fish plate and the inner marginal edge of the clip bears against the bolt heads to prevent the latter from being casually displaced. The outer fish plate is engaged by a pair of filler plates 14, the body of each of which overlaps the base of the outer fish plate and the base flange of the rail and engages beneath the clip 10. It will be noted that a portion 14 of each filler plate is extended inwardly to provide a lug 15 which bears against one terminal of the outer fish plate to further prevent longitudinal displacement of the fish plate. The filler plates 14 are secured to the base plate 8 of the rail chair by bifurcated keys 16, the keys being inserted from the bottom of the base plate and having the branches of the bifurcation bent outwardly into engagement with the top of the filler plate. It will be noted, upon reference to Fig. 1 of the drawings, that a portion of the web 10 is removed to provide an opening 17 through which access is gained to the bifurcated ends of the keys. The filler plates 14 slide beneath the nuts 13 in order to lock the latter from rotation and consequently when it is desired to remove the fish plates it is necessary that the keys 16 be first withdrawn, after which the filler plates 14 are disengaged and the fish plates may then be removed in an obvious manner. Furthermore, the rails may then be disengaged from their chair in an apparent manner.

The rail chair 7 which is only used where the rail is not jointed, embodies a base plate 8' having superimposed clips 9' and 10' detachably mounted thereon. When this form of chair is employed only outside fish plates 12' are used, the bases of which are elongated, as indicated at 18, so as to extend downwardly into engagement with the top of the base plate 8'. The fish plates 12' are secured from displacement by bifurcated keys 16' which are used in the same manner as the keys 16. The clip 10' on the other

side of the rail directly impinges against the top of the base flange, as illustrated in Figs. 1 and 2. In the use of this type of chair the rail 11' is first engaged beneath the clip 10', after which the fish plates 12' are engaged with the rail beneath the clip 9', as above described. When it is desired to disengage the rail 11' from the chair the keys 16' are removed and the fish plates 12' disengaged from the clips 9'.

The present invention provides a substantial rail supporting structure which reduces to an absolute minimum the number of ties used, in addition to eliminating the use of spikes. The rail chairs herein used not only support the rails on the ties but likewise join together the beams of each tie unit. Displacement of the rails is prevented, yet the rails may be readily removed from the chairs when desired.

It is to be understood that various changes may be made in this invention within the scope of the claims hereto appended.

What I claim is:—

1. A device as set forth, including a rail chair composed of a base plate with superimposed clips, fish plates slidable beneath said clips and engageable with the base plate, and filler plates slidable beneath certain of said clips in overlapping engagement with the fish plates, a portion of one terminal of each plate being extended to limit inward movement of the plate.

2. A combined rail tie and chairs including a pair of I beams equipped with angle iron anchoring elements on the bottom faces

thereof and spanning the distance therebetween, and rail receiving chairs mounted on the upper faces of the beams and secured thereto in parallel relation to the anchoring elements.

3. A combined rail tie and chairs including a pair of I beams equipped with angle iron anchoring elements on the bottom faces thereof, rail receiving chairs mounted on the upper faces of the beams and secured thereto in parallel relation to the anchoring elements, fish plates engageable with said rails and in the chairs, and filler plates for securing the rails and fish plates to the chairs.

4. In combination with a rail embraced by fish plates, a rail chair including a base plate with a superimposed clip having an intermediate portion thereof removed, a filler plate slidably inserted between the clip and fish plate, and means engageable through the base plate and filler plate and projecting into the space in the intermediate portion of the clip to hold the filler plates from movement.

5. A device as set forth including a base plate with superimposed clips, fish plates slidable beneath said clips, filler plates interposed between the clips and fish plates one margin of the outer end of each of which is extended to form a lug for limiting the inward movement of the plate, and means engaged through the base plate and the inner ends of the filler plates to secure the latter from displacement.

In testimony whereof I affix my name.
JAMES ASHMAN.
